92,511

DESIGN FOR A RAILWAY CAR

Norman Bel Geddes, New York, N. Y.

Application October 12, 1933, Serial No. 49,473

Term of patent 14 years

To all whom it may concern:

Be it known that I, NORMAN BEL GEDDES, a citizen of the United States, residing in the Borough of Manhattan, city, county, and State of New York, have invented a certain new, original, and ornamental Design for Railway Cars, of which the following is a specification, reference being had to the accompanying drawing, forming a part thereof, in which—

Figure 1 is a perspective view of a railway car embodying my design; and

Fig. 2 is a diagrammatic outline of a transverse section thereof taken on the line 2—2 of Fig. 1.

The dominant feature of my design consists in the form and contour of the shell of the car.

I claim:

The ornamental design for a railway car substantially as shown and described.

Signed this 11th day of October, 1933.

NORMAN BEL GEDDES.
